[57] CLAIM

The ornamental design for a body for a bottle, as shown and described.

DESCRIPTION

FIG. 1 is a top front left side perspective view of a body for a bottle showing our new design;

FIG. 2 is a front elevation, the rear and side elevations are the same;

FIG. 3 is a top plan view thereof;

FIG. 4 is a bottom plan view thereof; and,

FIG. 5 is a fragmentary cross sectional view showing the bottom of the body for a bottle.

The broken lines showing a bottle neck are for illustrative purposes only and do not form part of the claimed design.
